Attorney's

UNITED STATES PATENT OFFICE

GEORGE W. HURST, OF HAWTHORNE, NEVADA.

GATE.

No. 916,873.

Specification of Letters Patent. Patented March 30, 1903.

Application filed March 4, 1907. Serial No. 360,423.

To all whom it may concern:

Be it known that I, GEORGE W. HURST, a citizen of the United States, residing at Hawthorne, in the county of Esmeralda, State of Nevada, have invented certain new and useful Improvements in Gates; and I do hereby declare the following to be a full, clear, and exact description of the invention, such as will enable others skilled in the art to which it appertains to make and use the same.

This invention relates to gates and more particularly to that class which are designed to be opened by hand from a distance and the primary object of the invention is to provide a gate of this class having a shiftable upper hinge which may be moved by the gate operating mechanism to cause the gate to open in either direction desired.

In carrying out my invention I employ a V-shaped guide in which the inner vertical bar of the gate is designed to work and in which it is shifted by means of slotted plates which are arranged above the guide and through the slots of which the upper ends of the vertical bar project. I also employ in connection with the gate an automatic latch from engagement with which the gate is designed to be lifted by means of a swinging yoke member carried by the gate hinge post, this yoke being operated immediately preceding the movement of the plates to shift the vertical bar of the gate.

In the accompanying drawings, Figure 1 is a side elevation of the gate showing the gate in closed position, Fig. 2 is a front elevation thereof, Fig. 3 is a top plan view showing the gate in open position, Fig. 4 is a similar view showing the gate in closed position, Fig. 5 is a view similar to Fig. 4 but with a portion of the plates broken away to show the guide member for the vertical bar of the gate, and Fig. 6 is a detail view in elevation of the keeper post for the gate showing the normal position of the keepers.

Referring more specifically to the drawings the numeral 10 denotes the hinge post of the gate, and 11 the latch post therefor.

The gate proper comprises upper and lower horizontal bars 12, an inner vertical bar 13, which extends considerably above the upper horizontal bar and slightly below the lower horizontal bar and an outer vertical bar 14 beyond which the outer ends of the upper and lower horizontal bars 12 project as at 15.

The filling of the gate may be of any desired material and construction for example a wire

screen. The lower end of the inner vertical bar 13 of the gate is supported by means of a bracket which comprises an attaching portion 16 which is secured to the gate post 10 and which has its upper portion bent outwardly and thence back upon itself as at 17, the outwardly bent portion being provided with a socket 18 and the returned portion 17 with an opening 19 through which the lower end of the vertical bar 13 projects, the extreme lower end of this bar being seated in the socket 18 which is of less diameter than the opening 19 in the bracket.

Supported upon the upper end of the gate post 10 is a plate 20 from which projects a V-shaped guide preferably formed of inner and outer V-shaped members 21 and 22 respectively which are equidistantly spaced and project in the direction of the latch post 11. The upper end portion of the inner vertical bar 13 projects between these V-shaped members and is movable therebetween in a manner to be presently described. Swiveled upon the plate 20 are plates 23 and 24 which are substantially triangular in form and overlap, the plate 23 being above the plate 24. These plates are pivoted to the plate 20 at corresponding corners and formed in each of the plates and extending from a point adjacent their point of pivotal connection with the plate 20 to their adjacent corners are slots 25 and 26 respectively which are at all times in registration with each other to a greater or less degree and through which projects the extreme upper end of the vertical post 13 of the gate it being understood that these slotted corners of the plates 23 and 24 project over the guide members 21 and 22.

Arranged upon opposite sides of the gate post 10 and to some little distance therefrom are uprights 27 and 28 upon which are pivotally mounted levers 29 and 30 respectively. These levers are pivoted substantially at their middle and normally extend obliquely upward and secured at one of its ends to the upper end of the lever 29 is a cable 31 which cable is attached at its opposite end to the remaining corner of the triangular plate 23 and to this corner is also connected one end of a cable 32 which is secured at its opposite end on lever 30 at a point below the point of pivotal connection of the lever with the post.

A cable 33 is connected at one of its ends to the upper end of the lever 30 and extends

95

100

105

110

to and is connected with the corresponding corner of the plate 24 and connecting this corner of the plate and the lever 29 below the pivotal point of the same is a cable 34.

- 5 Secured at their corresponding ends to the gate post 10 are cables 35 and 36 which are connected at their outer ends to the levers 29 and 30 respectively and these cables pass under the side portions 37 of a yoke member 10 38, the ends of the said portions being pivotally connected with opposite sides of the gate post 10. The inner vertical bar 13 of the gate is confined within this yoke and is adapted to be moved by the raising of the 15 yoke from its normal position which is in a substantially horizontal plane, to a vertical plane. The cables 35 and 36 are so stretched that movement of the levers will cause them to act upon the yoke member to raise the 20 front of the gate and one of the plates 23 or 24 will positively move to move the upper end of the vertical gate bar into one side or the other of the guide and consequently insure automatic swinging of the gate in that 25 direction due to its own weight and the change of location of the upper pivotal point of the gate.

The cables hereinbefore described are preferably passed around pulleys 39 carried by 30 posts 40 which are arranged intermediate the post 10 and the posts 27 and 28. As clearly shown in the drawings the normal position of the gate is such that the vertical end bar 13 is inclined and in order to fill the space between this bar and the gate post 10 I provide upon the post a flange 41, which may be made of wood or metal and may be secured in any suitable manner to the post.

The latch for the gate comprises two pairs 40 of keepers 44 each of which comprises a strip of metal bent back upon itself as at 45 and pivoted as at 46 upon the latch post. The members of each pair are pivoted one above the other and the corresponding members of 45 the two pairs oppose each other and in order that the two pairs may be moved in unison the members of each pair are connected by means of a bar 47.

From the foregoing it will be seen that as 50 the gate is swung to closed position, the projecting ends of the upper and lower gate

bars 11 and 12 move over the upper edges of the keepers and rest between the opposing ends of the corresponding ones of the pairs of keepers, it being furthermore understood 55 that owing to the initial tilting of the gate before being swung, the projecting ends of the said bars are raised out of such engagement between the keepers. Furthermore the bars 47 may be grasped and the keepers 60 moved to permit of opening of the gate by a person traveling on foot.

What is claimed is—

1. A device of the class described comprising a gate post, a bracket carried by the 65 post, a V-shaped guide supported by the post at its upper end, a gate having a vertical bar extending above its top horizontal bar, the lower end of said vertical bar being seated in the bracket and the upper end being engaged with the guide, a yoke pivoted upon the post and inclosing the vertical bar, means for swinging the yoke from a horizontal to a vertical position to tilt the gate through the medium of the vertical bar, and 70 means arranged above the guide for directing the bar after being tilted, into one or the other portion of the V-shaped guide.

2. A device of the class described comprising a gate post, a bracket carried by the 80 post, a V-shaped guide supported by the post at its upper end, a gate having a vertical bar extending above its top horizontal bar, the lower end of said vertical bar being seated in the bracket and the upper end being engaged with the guide, a yoke pivoted upon the post and inclosing the vertical bar, plates pivoted upon the upper end of the 85 gate post and provided with slots which register and through which the upper end of the vertical bar projects, and means for moving 90 one or the other of the plates positively to shift the upper end of the vertical bar into one or the other of the portions of the V-shaped guide.

In testimony whereof, I affix my signature, in presence of two witnesses.

GEORGE W. HURST.
